ARTHUR W. HELMHOLTZ AND DENT FERRELL, OF HARRISBURG, ILLINOIS, ASSIGNEES
TO SAFETY MINING COMPANY, OF HARRISBURG, ILLINOIS, A CORPORATION OF
ILLINOIS

SHELL FOR BLASTING CARTRIDGES

Application filed June 23, 1928. Serial No. 287,864.

This invention relates to improvements in blasting cartridges and particularly to the type of cartridge having a rigid casing containing a suitable blasting medium under pressure and has means for releasing or discharging the blasting medium upon predetermined conditions, and concentrating and directing the discharged fluid in a predetermined direction or directions.

10 This invention relates particularly to the type of cartridge shown in the applicant's co-pending application, Serial No. 169,441, filed February 19, 1927, for improvements in blasting cartridges. It will be noted that the 15 cartridge therein disclosed is one having a refillable rigid casing adapted to contain a substance gaseous at ordinary temperatures and pressures such as, for example, carbon dioxide, and is further provided with a re- 20 leaseable end wall, a discharge nozzle and means for artificially and internally heating the blasting medium. In operation, the blasting medium is ignited by means of an electric current which artificially raises the temper- 25 ature of the compressed carbon dioxide to and above its critical temperature to cause the development of an excessive pressure within the cartridge. The pressure developed is greater than the predetermined pressure 30 at which the end wall ruptures. By accurately adjusting the behavior of the respective parts a discharge of the cartridge causes a rapid heating, agitation and vaporization of the carbon dioxide, the development of 35 excessive pressure and the release of the end wall, and the concentration and directing of the discharging gases in a substantially instantaneous time interval.

One of the objects of the present invention is to provide a method by which the rigid casing for cartridges of this type may be made from metal alloy which retains its original qualities after the forming operation of the seamless drawn tube and one in 45 which the undesirable cracking and lamination at important points, such as at the knife edges, is eliminated.

Another object is to provide a cartridge shell which has an improved throat or nozzle 50 area at the discharge end, the configuration

of which has been determined after long experiment and study and is one causing the blasting medium in the container after gasification by artificial heat to escape from the shell in the smallest interval of time without 55 creating eddy currents or becoming wire-drawn to an extent which would diminish the velocity of efflux and cause loss of pressure.

The invention is illustrated as applied to a 60 cartridge in which the maximum nozzleing effect is obtained, and further, one in which the nozzle construction is continued into the spaces in the interior of the discharge cap, and finally to the exit holes located in the circumference of the discharge cap positioned 65 at substantially 90° to the axis of the cartridge.

The present disclosure illustrates a cartridge in which the discharge cap is constructed with a solid end wall having a deflecting curve on its inner surface, which wall and curve serve to counteract the initial 70 velocity rush of the issuing blasting medium and to deflect the gas to the exit nozzles 75 in the cap circumference with the least amount of friction and loss of pressure.

These and other objects are accomplished by means of the arrangement disclosed on the accompanying sheet of drawing, in which— 80

Figure 1 is a side elevational view of a cartridge similar to that shown in the co-pending application referred to and embodying the novel features of the present invention; 85

Figure 2 is an enlarged cross sectional view of the cartridge shown in Figure 1, disclosing the internal construction of the shell and cap forming the nozzle.

The various novel features of the invention will be apparent from the following description and will be particularly pointed out in the appended claims.

Inasmuch as the present invention is illustrated as applied to a cartridge substantially like that disclosed in the co-pending application above referred to, the present disclosure is limited to just such parts as are necessary for a clear understanding of this invention. 100

tion, attention being directed to the prior disclosure for the omitted parts.

By referring to the drawing, it will be noted that the present invention relates to a cartridge having a refillable cylindrical casing 10, having a discharge end 11 of reduced diameter with a tapered internal shoulder 12. In producing the shell for this cartridge by the improved method, it is originally formed to a shape indicated by the outline 12 as shown in Figure 2. The inward shoulder 12 and the internal diameter of the casing, except for the nozzle portion, are determined at the time of the initial forming operation. There is an excess of metal, however, provided over the exterior of the surface and on the inside of the nozzle. The casing or barrel of the shell, by a machining operation, is first cut down throughout its entire length to the exterior dimension 13.

By additional machining on the exterior of the discharged end the reduced portion 11 is provided forming the shoulder 14 which extends parallel to the internal shoulder 12 and so spaced therefrom as to provide a wall of suitable strength and thickness and substantially equal to the wall portion of the main body of the shell or barrel. The outside of the end portion is then threaded, as shown, for receiving the cap member, and the interior of the nozzle, which is also provided initially with excess metal as shown in 15, is cut down to the finished surface 16. The knife edges may then be provided by machining on the outer edge to the shape shown in the drawing. It has been found in practice that machining the metal barrel to the shape shown, after a simple forming operation, results in unaltered metal at the locations of greatest importance, that is at the nozzle, throat and knife edge seals, respectively.

After machining these locations are specially hardened by heat treatment under controlled temperatures, and cartridges suitable for exceptional service are obtained by this process resulting in long life to the rigid container.

By machining the reduced end, instead of swedging or otherwise hydraulically forging it, a better cartridge is produced, because in a swedging operation the end of the shell is heated only once and then the metal forced into form by machine means which tends to produce a cold working of the metal, thus hardening it without control of temperature, which latter causes the metal at the place of greatest contraction or working to split and laminate or otherwise become weakened or fractured under strain.

On the end of the casing 11 the cap 17 is threaded, the parts being so constructed that the outer periphery of the cap is a continuation of the outer cylindrical surface of the

barrel. The interior of the cap is provided with a cavity 18, nozzle portion 19 and radially disposed openings 20 and also with a shoulder 21 for securing, when the cap is in place, the shear ring 22, and the rupturable end wall 23 in place against the knife edge or edges as shown in the drawing. The nozzle portion 19 is flared and is shaped to form a continuation of the nozzle surface 16 in the end of the barrel. The inner surface 24 of the shear ring is likewise flared to produce a continuation of the nozzle. In the particular form therein illustrated the nozzle effect is carried to the radial outlets 20, which are provided with flared surfaces 25 to effect an outward enlargement of the opening, it being understood, however, that this is not absolutely necessary. The end wall of the cap is provided on the inside with the curved surface 26, which may take the form of an inwardly extending cone and may be replaceable and which is found to produce a desirable effect in directing the discharging gases out of the openings 20 and also in offering a resistance in opposition to the opposite end wall of the cartridge for preventing bodily displacement of the cartridge in the drill hole upon discharge. The opening 27 may be provided in the end wall for permitting the introduction of a tool or other means employed for refilling the cartridges. The opening 27 is relatively small and does not impair to a substantial extent the function assigned to the inner surface of the end wall. The particular flare of the nozzle illustrated is designed in accordance with data secured from numerous experiments giving the proper dimensions to insure the proper velocity of efflux of the gas so that the container is capable of completely discharging its contents through the ruptured wall or disk into the interior space of the discharge cap in an interval of time comparatively instantaneous.

The nozzle construction of the interior of the cap and the outlets therein allow the blasting medium to continue on its path to the drill hole without great loss in velocity and pressure which results in the doing of maximum work in the drill hole.

The instantaneous transfer of heat from a suitable heating element to the blasting medium accompanied by violent agitation and resulting rise in pressure of the blasting medium to the rupturing strength of the wall or disk, all as described in the co-pending application referred to, and the nozzleing of the exit throat of the container and the likewise nozzle construction of the cap interior, together with the directive power of these exits in the application of gas pressure on the coal or other body to be broken down, as well as the minimum of voids about the exterior of the shell and the drill hole, are the main reasons for the efficient action of the

blasting medium in the work of loosening materials. Other reasons are the large number of cubic feet of gas per pound of blasting medium, the low temperature to which it has to be heated to render it gaseous and to create a pressure sufficient to rupture the wall or disk at the end of the container and the slow rate of cooling of the gaseous blasting medium due to such low temperatures.

10 As compared with black powder, the combustion temperature of the latter is in the neighborhood of 3500° F. Its gas content is about four cubic feet per pound, hence its rate of cooling is extremely fast. In the case of 15 carbon dioxide, the temperature of heating is only 400°, and the cubic feet per pound are eight, and its rate of cooling is therefore tremendously lower than that of black powder.

The combustion temperatures of the dynamites are even higher than the figure given for black powder, and consequently the cooling gradient is also much steeper.

Still another factor enters in the case of carbon dioxide as blasting medium when compared with the powders and dynamites. The specific weight of the former when at atmospheric temperature and pressure is 1.5 times that of air while the gases from the combustion of the powders and dynamites in the same state is probably a little less than 1.0 or perhaps 1.0 when compared with air. Under the same degree of temperature rise and pressure the pure carbon dioxide gas will have a greater range of action due to its increased 35 momentum over the gases from the other explosives. This accounts partly for the great penetrating and spreading power of the carbon dioxide gas and its pushing or prying action in coal while in the case of the powders 40 the gases rather hit a blow on the coal without much spreading action.

It has already been mentioned in the pending application referred to that another function of the solid end in the discharge cap 45 and the discharge of the blasting medium at right angles, more or less, to the main container axis, is to cause the initial velocity rush of the gas, which is exceedingly high, to be substantially compensated for and thereby 50 eliminate the tendency of the container to move backward in the drill hole. Movement in the drill hole is objectionable in that it causes a large extra void to be made at the discharge end of the shell and also backing 55 up on the conductors attached to the valve cap at the charge end of the shell, damaging them or causing short circuit between them.

It will be obvious from the above that the directing action of the nozzle openings 20 in the cap circumference causes a greater portion of the gasified blasting medium to be applied to the drill hole in the coal or other body to be broken down at an angle of about 90° to the main axis of the rigid container. This 60 gives a wider transverse area of action or

application of the blasting medium and results in an increase in material broken loose, a cleaner shear in the ribs of the coal or other body and a cleaner and more efficient detachment of the coal or other body from the breast. In addition the deviation of a large part of the blasting medium from contact and action on the roof of the coal body causes the breaking and loosening action upon the roof rock and slate to be satisfactorily light, and goes far to diminish the maintenance cost of the roof.

It will further appear that the container is one having a constant overall dimension which may be inserted into a drill hole cut with a constant diameter and with small clearance over the diameter of the shell without excess space about the container. This elimination of voids or excess space about the container makes for a maximum of efficiency in the action of the pressure exerted upon discharge. In addition the presence of moisture or running water in the drill hole, coal or other body to be broken down, is no detriment to the operation, but is rather an aid to the blasting operation, in that the water accumulates in the drill hole about the shell after it is tamped in place and effectively fills whatever voids there happens to be present.

We claim:

1. A cartridge of the character described, having a nozzle and a cap, having an inwardly projecting rounded end wall disposed in opposition to the end of said nozzle.
2. A blasting cartridge comprising a casing having a tapered discharge nozzle, a closure for the end of said nozzle and cap associated with said nozzle and having a tapered passage forming a continuation of said nozzle.
3. A blasting cartridge comprising a casing having a discharge passage, a cap for said casing having a chamber, and a plurality of radially arranged tapered discharge orifices in said cap.
4. A blasting cartridge comprising a casing having a tapered discharge nozzle, a closure for the end of said nozzle, a cap associated with said nozzle and having a tapered passage forming a continuation of said nozzle and a plurality of radially arranged tapered outlets communicating with said passage.
5. A blasting cartridge comprising a casing having a discharge opening tapering from the inside outwardly and a cap associated with said casing and having a correspondingly tapered passage forming a continuation of said discharge opening.

6. A blasting cartridge embodying an outwardly tapered discharge passage with a convex deflecting wall arranged in opposition thereto, and a plurality of radially arranged discharge ports communicating with said passage adjacent said wall.

7. A blasting cartridge comprising a casing having a tapered discharge passage, a rupturable disc disposed over the end of said passage, a shear ring arranged adjacent said disc, and a cap adjustably connected with said casing and having a part engaging said shear ring, said cap and shear ring being formed with a tapered passage in continuation of the aforesaid tapered passage.

5 Signed at Duquoin, Illinois, this 16th day
0 of June, 1928.
